UNITED STATES PATENT OFFICE.

EPPE M. LUCUS, OF VAN ALSTYNE, TEXAS.

HYDROCARBON-BURNER.

1,206,559.

Specification of Letters Patent. Patented Nov. 28, 1916.

Application filed July 3, 1916. Serial No. 107,268.

To all whom it may concern:

Be it known that I, EPPE M. LUCUS, a citizen of the United States of America, residing at Van Alstyne, county of Grayson, 5 Texas, have invented a certain new and useful Improvement in Hydrocarbon-Burners, of which the following is a specification.

This invention relates to a new and useful form of improvement in an oil burner, and 10 particularly a hydrocarbon fuel oil burner.

A purpose of the invention is to provide a type of burner highly useful and adaptable for household utility and general utility use for suburban homes and other 15 places where gas is inaccessible.

In this particular instance and form of the invention it is a purpose to provide a hydrocarbon burner consisting of a rectangular base member upon which is arranged 20 a pair of burner tubes in connection with certain control arrangements hereinafter described.

A further purpose of the invention is to provide an oil burner which will have an 25 air regulating and controlling means by which the air supply feed to the burners may be varied, thereby insuring a perfectly adjustable combustion mixture whether the burner device is used in an open grate, stove 30 or strong draft chimney.

With the above and other objects in view the invention resides in the certain form and combination and arrangement of parts and elements as described in the following 35 specification, specifically pointed out in the appended claims and illustrated in the accompanying drawings, wherein:

Figure 1 represents the burner in plan view. Fig. 2 illustrates the invention and 40 present form of burner device in elevation, a portion of said illustration being shown in longitudinal sectional view. Fig. 3 shows the bottom of the burner. Fig. 4 shows a cross sectional view taken upon the line 4—4 of Fig. 3. Fig. 5 is a sectional view taken upon the line 5—5 of Fig. 1. Fig. 6 shows a bottom view of the burner device with a number of parts removed, particularly 45 illustrating a certain form of slide valve used in connection with the burner.

Referring now more in particular to the drawings, wherein the same reference characters are used to designate identical parts throughout, the numeral 1 indicates the 50 burner base of the device. A side wall or depending web 2 is provided and has con-

nection with the burner base, by being secured and fixed to lugs 3, which lugs are integrally formed on the under side of the burner base and lie in fixed contact with the 50 wall 2. A pair of U-shaped burner tubes 4 are arranged upon the base as shown in the illustrations and have connection with a fuel oil supply tube 5 which furnishes fuel from a reservoir conveniently located somewhere above the burner device but not here illustrated. Control valves 6 are included in the pipe connections which feed the burner tube and each valve is provided with a hand wheel which insures easy control of 65 the oil flow to said burner tube. Union connection 7 is included in the pipe connections extending to the tubes which insures the easy removal of the burner tube when it may be necessary to dismantle it for cleaning or for other reasons. Burner caps 8 are provided with a substantially small burner aperture or jet formed therein. An oil receptacle sump 10 is formed in the base beneath each burner cap and jet and is 70 formed there for the purpose of catching and retaining a small supply of fuel oil which may be burned in the sump and which burning will generate the oil contained in the tube into gas to be consumed at the jet. 75

A number of hollow air nozzles 8^a are cast and integrally formed in the burner base and arranged about the burner jet in a cluster as illustrated. The upper extremities of the air nozzles are formed on an angle with the horizontal. Said air nozzles have their upper extremities inclined toward the burner jet. The nozzles are hollow in form and communicate with an opening 85 formed in the base which arrangement allows the air nozzles to convey air from the internal portions of the grate or stove in which the burner may be installed to the point of combustion. A flame spreader or deflector disk 11 is carried by each burner tube and adapted to be arranged in horizontal position just above the burner jet. A slide plate 12 is provided in sliding contact on and against the underneath surface of the burner base. The said slide plate has its 90 length and width substantially the same as the dimensions of the burner base and is adapted to have its edges positioned in contact with the side walls 2. A pair of support members 13 are fixed to the side walls 2 and adapted to support the slide plate 12 95 in contact with the burner base. A slot 14 is 100 105 110 115

formed in the end walls as clearly illustrated in Fig. 6 and is adapted to admit of the passage of a portion of the slide plate therethrough. A rod member 15 with an upturned handle 16 is supported in a guide bracket 17 and has fixed connection with the slide plate. The slide plate is provided with ears 18, which ears are adapted to overlap the apertures or openings leading through the base to the open air nozzles which convey air to a point adjacent to the point of combustion or flame around and about the burner jet. By the use of the handle 16 the slide plate or valve may be moved along the burner base either opening or closing the two apertures of each set leading to the air nozzles or by proper adjustment the openings may be varied in size, thereby regulating the quantity of air flowing upward through the air nozzles to the burner jet. An elongated slot or opening 19 is formed in the slide plate admitting the unobstructed movement of the slide plate along the oil tube which passes upwardly through the base.

For economy in fuel oil consumption the burners may be used independently one of the other, the combustion mixture being regulated by the valve 6 and air regulating means as described. To place in proper burning condition a small amount of oil will be admitted to the sump 10 and ignited after which the valve 6 will again be opened slowly until proper combustion takes place.

The invention is intended to include all such modifications and changes as may properly come within the purview of the included claims.

Claims.

1. In a hydrocarbon burner, the combination with a base, of a pair of burner tubes arranged upon the base, a burner jet carried

by each burner tube, air nozzles clustered about the burner jets, said air nozzles having an inclined position toward the burner jets, 45 a slide plate held in contact with the underneath surface of the base, and projecting ears formed on the slide plate adapted to pass over and close the air nozzles.

2. In a hydrocarbon burner, the combination with a base, of a pair of burner tubes arranged upon the base, a burner jet carried by each burner tube, air nozzles clustered about the burner jets, said air nozzles having an inclined position toward the 55 burner jets, a slide plate held in contact with the underneath surface of the base, projecting ears formed on the slide plate adapted to pass over the air nozzles, and an upturned handle rod having connection with 60 the slide plate adapted to vary the position of said slide plate.

3. In a hydrocarbon burner, a base member, a downturned web or wall formed on the base, burner tubes arranged upon the 65 base and having connection with a supply tube, a plurality of air nozzles formed in the base and adapted to draw air from underneath the base through apertures formed therein, a slide valve supported under the 70 base and in contact with said base and guided by the side walls, a plurality of extended ears formed on the slide valve and in line with the air nozzle apertures, a slot formed in the wall adapted to allow the passage of the slide plate, and a handle connected with the slide valve.

In testimony whereof I affix my signature in the presence of two witnesses.

EPPE M. LUCUS.
